UNITED STATES PATENT OFFICE

137,508

DESIGN FOR A HEADLIGHT BULB

Lillian Malinda Asay, Camden, N. J.

Application June 24, 1943, Serial No. 110,518

Term of patent 14 years

(Cl. 26—8)

To all whom it may concern:

Be it known that I, Lillian M. Asay, a citizen of the United States, residing at Camden, in the county of Camden and State of New Jersey, have invented a new, original, and ornamental Design for a Headlight Bulb, of which the following is a specification, reference being had to the accompanying drawing, forming part thereof.

I claim:

The ornamental design for a headlight bulb, as shown.

LILLIAN MALINDA ASAY.
